(57) **CLAIM**

I claim the ornamental design for a resilient electric Christmas light wrap for tree, as shown and described.

DESCRIPTION

FIG. 1 is a perspective view of a resilient electric Christmas light wrap for tree showing my new design;

FIG. 2 is a side elevational view thereof;

FIG. 3 is an elevational view of an opposing side thereof;

FIG. 4 is a top plan view thereof;

FIG. 5 is a bottom plan view thereof; and,

FIG. 6 is a perspective view showing the resilient electric Christmas light wrap for tree in use; the phantom lines depict environmental structure for illustrative purposes only and form no part of the claimed design.
